CONTROL SYSTEMS

Russell E. Fredrick, White Bear Lake, Minn., assignor, by mesne assignments, to Minnesota Mining and Manufacturing Company, St. Paul, Minn., a corporation of Delaware

Filed May 29, 1958, Ser. No. 738,874

7 Claims. (Cl. 158—131)

My present invention relates to improvements in control systems, and more particularly to control systems including control means and a plurality of thermoelectric generator means, each subject to a heat source, and in which at a predetermined temperature at any one of the hot thermojunctions thereof, actuation of the control means is effected.

In many instances it is desirable in a control system including a plurality of energized devices to afford actuation of control means of the system upon a predetermined reduction in temperature at any one of the energized devices, and accordingly it is an object of my invention to provide a simple, efficient and economic control system to that end.

My present invention may, by way of example, have typical utility for a control system including a plurality of primary gas burners supplied with fluid fuel from a common supply manifold, and in which suitable main control valve means is associated with the supply manifold to terminate the supply of fluid fuel to all the primary burners when the temperature at any one of the plurality of ignition burners drops below a predetermined temperature. In the application in my invention in the instance noted, I comprehend the provision of thermoelectric generator means, one associated, for example, with a pilot burner for each primary burner, and in which the several thermoelectric generators are in circuit with coil means of the main control valve means to effect actuation of the latter upon the diminution or failure of any one of the pilot burners so as to shut off fluid fuel to all the primary burners. To this end, each thermoelectric generator means, to achieve the aforementioned control in accordance with my invention, includes at least one thermoelectric element having a high negative temperature coefficient of resistance at and below a predetermined operating temperature so that upon diminution or extinguishment of heat at the hot thermojunctions thereof, the resistance of the control circuit is markedly altered to actuate the main control valve means in the circuit to close off the supply of fluid fuel to all of the primary burners.

A further object of my invention is to provide a control system for a plurality of primary heating devices with which secondary igniting devices are associated, control means for controlling supply of fluid fuel to the primary heating devices, thermoelectric generator means at each secondary igniting device in circuit with the control means, and in which each thermoelectric generator means includes at least one thermoelectric member having a negative temperature coefficient of resistance so that at a temperature below a predetermined temperature at any one of the hot thermojunctions of the thermoelectric generator means, the resistance of the circuit is increased so that the control means terminates the supply of fluid fuel to the primary burners.

The above and other objects and advantage of my invention will appear from the following detailed description of a preferred embodiment of my invention.

Now in order to acquaint those skilled in the art with the manner of constructing and utilizing a control system in accordance with my invention, I shall describe in connection with the accompanying drawings a preferred embodiment of my invention.

2

In the drawings:

FIGURE 1 is a schematic representation of a control system constructed in accordance with my invention and embodied with a plurality of fluid fuel burners;

5 FIGURE 2 is a longitudinal cross-sectional view of a thermoelectric generator suitable for use in the system of FIGURE 1;

FIGURE 3 is a graphic illustration of the general thermoelectric power characteristics in micro volts/° F. over a selected temperature range of a number of thermoelectric elements having utility for this invention composed of manganese and tellurium within the hereinafter disclosed range, and said range of manganese and tellurium including certain additions of positive promoters therein; and

10 FIGURE 4 is a graphic representation of the temperature dependence of the electrical resistivity expressed in ohm-inches log scale, plotted against the reciprocal of absolute (Kelvin) temperature, symbolically expressed as $10^3/T^{\circ}$ K., of certain thermoelectric elements having utility for this invention composed of manganese and tellurium within the hereinafter disclosed range, and said range of manganese and tellurium including additions of positive promoters therein.

15 20 25 Referring now to FIGURE 1 of the drawings, I have shown a control system indicated generally at 3, comprising control means 4, which in the embodiment selected for disclosing my invention comprises a safety device or main valve control means, a plurality of main or primary gas burners 6 and 7, and a plurality of ignition or secondary burners 8 and 9 are for the main or primary burners 6 and 7, respectively.

20 25 30 35 40 45 The control means 4 shown in the drawings is a well known automatic shut-off device and for purposes of the present disclosure it is sufficient to note that it comprises a housing or casing 12 provided with an inlet opening 13 and an outlet opening 14. The inlet opening 13 extends to an inlet chamber 15, and an outlet opening 14 connects with outlet chamber 16, the two chambers being separated by a partition 17 affording upper and lower valve seats 18 and 19, respectively. A valve 20 disposed in inlet chamber 15 has an armature 22 at its upper end, which is adapted to cooperate with an electromagnet 23 including coil means 24 which when energized creates a magnetic field sufficient to hold the armature 22 attracted and valve 20 in open position with respect to valve seat 18 so that fluid fuel admitted through inlet opening 13 passes through the inlet chamber 15, partition 17, outlet chamber 16, and outlet opening 14. A suitable cage indicated at 25 provides for the support of valve 20 for reciprocal axial movement and for support of the electromagnetic device shown at 23 all in a known and conventional manner.

45 50 55 60 65 70 75 80 85 90 95 The safety device or control means 4 further comprises reciprocal reset means 30 having a manually actuating button 32 and carrying at its inner end a valve 33 adapted to cooperate with valve seat 19 to close off the flow of fluid fuel through the valve. The reset means 30 includes spring means indicated at 36 and 37 to afford for normal disposition of valve 33 in open relation with respect to valve seat 19. When the coil means 24 is deenergized or insufficiently energized, armature 22 is released and valve 20 closes valve 18 to shut off flow of fluid fuel through the valve. Under such conditions, the reset stem 30 may be urged upwardly from the position shown in the drawings to a position wherein the projecting end 38 of stem 30 engages the bottom of valve 20 to dispose the armature 22 in position against the electromagnet, and if the latter is adequately energized by the coil 24, the electromagnet retains valve 20 in the position shown in the drawings to afford the flow of fluid fuel through the valve.

As shown, a main manifold 40 extends from the outlet chamber 16 of the safety device 4, and branch connection 41 and 42 lead, respectively, to the main or primary burners 6 and 7. Also, in the arrangement shown, a second pilot or igniter manifold 43 has connection with a port 44 extending through partition 17 opening into the latter intermediate valve seats 18 and 19. The secondary manifold 43 also comprises branch conduits 46 and 47, which extend to the secondary burners or igniters 8 and 9, respectively.

Also, as illustrated in FIGURE 1 the coil means 24 of control means 4 is connected in series circuit relation with a pair of thermoelectric generators indicated generally at 50 and 52, each comprising a pair of thermoelectric elements 53 and 54. The thermoelectric generators 50 and 52 are of like construction and, as shown, circuit means 55 comprising leads 56 and 57 connect coil means 24 in series circuit relationship with the thermoelectric elements 53 and 54 of generators 50 and 52. The thermoelectric generators in this instance constitute single thermocouples, but it will be appreciated that thermopiles could be employed if desired. The hot thermojunctions 53 of both generators are adapted to be heated by the flame of the secondary or ignition burners 8 and 9.

In the operation of the control apparatus shown in FIGURE 1, it will be clear that when both igniters or secondary burners 8 and 9 are energized, the flames thereof heat the hot junctions 53 of both thermoelectric generators to afford an electric current sufficient to effect energization of electromagnet 23 to hold armature 22 in attracted position. In this position gas is free to flow through inlet 13 through the valve housing to outlet 14 to manifold 40 for the primary burners 41 and 42. Also in the position of the parts related gas flows through port 44, manifold 43, and branch conduits 46 and 47 to the secondary or ignition burners 8 and 9. The ignition burners 8 and 9, of course, afford for the ignition of the fluid fuel emanating from burners 6 and 7. Thus with the burners 6 and 7 energized and both pilots or igniters 8 and 9 in operation, the safety device 4 is maintained in open position and the system is in operation.

The thermoelectric generators 50 and 52 are characterized as above noted by a plurality of thermoelectric elements 53 and 54, and such thermoelectric elements are constructed of materials having different thermoelectric properties and for purposes of my present invention at least one of the thermoelectric elements has a high negative temperature coefficient of resistance. Let it be assumed that each of the thermoelectric elements 54 has a negative temperature coefficient of resistance at and below the normal predetermined operating temperature. It will then be apparent that upon extinguishment or predetermined diminution of the flame at either of the igniters or secondary burners 8 and 9, reducing the temperature of the associated hot thermojunction 53 below a predetermined temperature, the negative temperature coefficient of resistance of the thermoelectric element 54 comes into play to afford an increase in the electrical resistance in circuit means 55 so that insufficient current flows in coil 24 for the electromagnet 23 to retain the armature 22. When such temperature condition occurs the armature 22 is released, and valve 20 seats on valve seat 18 closing off the flow of fluid fuel to all the primary and secondary burners. The system cannot then be placed into operation without actuating reset means 30 to dispose armature 22 in juxtaposition of electromagnet 23 and reenergization of the secondary burners or igniters 8 and 9 must be effected. It will be seen that in utilizing the reset means 30, the valve 33 seats against seat 19 so that during the resetting operation fluid fuel is not free to flow through the main manifold 40, but fluid fuel does flow through the manifold 43 for the secondary burners or igniters 8 and 9. Upon reignition of the secondary burners or igniters 8 and 9 and sufficient heating of the hot thermojunctions 53 has occurred to generate current in coil 24

of electromagnet 23 to hold the armature 22 in attracted position, release of the reset means places the system again in operation. It will thus be seen that my invention affords control of the safety device 4 upon the occurrence of an undesirable or unsatisfactory condition at either of the secondary burners or igniters 8 or 9.

The generators 50 and 52 of my invention may take any number of forms and one suitable construction in that regard is shown in FIGURE 2 of the drawings. As shown in FIGURE 2 of the drawings, the thermoelectric element 54 may comprise certain manganese-tellurium compositions, hereinafter referred to in greater detail, and the second thermoelectric element may comprise a stainless steel enclosure 53. The outer or second thermoelectric element 53 comprises a heat probe portion 60 within which a contact electrode 62 is disposed. The contact 62 is suitably electrically joined to the closed outer end of heat probe 60 at hot thermojunction 53 and at its inner end has connection with the inner thermoelectric element 54. The outer thermoelectric element 53 as shown is secured to a sleeve 63 which may afford a heat sink for effecting cooling of the outer cold thermojunction means of the generator. The inner end of the thermoelectric element 54 at the inner cold thermojunction has a contact electrode 66 secured thereto and it is provided with a shank portion 67 extending coaxially of sleeve 63 and through openings provided in transverse bushing members 68 contained within the sleeve 63. A pair of disc compression springs 69 are arranged between bushings 68 with the arrangement providing for the maintaining of the inner thermoelectric element 54 under compression to strengthen the latter against breakage. In this connection it will be seen that one of the washers 68 seats against a shoulder within sleeve 63, and the other washer 68 is in abutment with the enlarged flanged end of the contact electrode 66 so that with the spring means 69 disposed therebetween a compressive biasing force is applied to the inner thermoelectric element 54. A conductor 70 extends from the contact electrode 66 and through an insulating sleeve 72 mounted adjacent the end of sleeve 63 opposite the hot thermojunction of the generator. The sleeve 63 has electrical connection with outer thermoelectric element 53 and at its outer end includes a metallic sleeve 73 which affords for the electrical connection of a lead thereto. As shown, the insulating sleeve 72 electrically insulates leads 70 and sleeve 73 from each other to afford for circuit connection of the generator in an electric circuit as for example with conductors 56 and 57 in circuit means 55 of FIGURE 1. The inner lead 70 is preferably provided with a loop or slack portion 75 which serves to prevent the transmission of shocks applied to the lead from reaching the contact 66 and inner thermoelectric element 54.

The entire generator assembly is preferably hermetically sealed to afford protection primarily for the inner thermoelectric member 54 which, when it is constituted of certain manganese-tellurium compositions hereinafter disclosed in detail, is subject to deleterious attack by oxygen and hence should be protected from oxygen. The seal structure at the end of sleeve 63 opposite the hot junction including conductors 70 and 73, and insulator 72 affords with the sleeve 63, and thermoelectric member 53 a hermetic enclosure for the thermoelectric member 54.

As above indicated the thermoelectric generator of the present invention comprises thermoelectric elements 53 and 54 of different thermoelectric characteristics, and at least one of the thermoelectric elements should possess a high negative temperature coefficient of resistance. By way of example the aforementioned compositions of manganese and tellurium disclosed in the copending application of myself and Clarence R. Manser, Serial No. 715,454, filed February 14, 1958, and now Patent No. 2,890,260, are well suited for this purpose. It is there disclosed that electrical conductor elements of good

thermoelectric and thermistor characteristics may comprise intermetallic compositions consisting essentially of manganese and tellurium within the range of from 69.9 percent to 72.0 percent by weight tellurium and the balance substantially all manganese. The aforementioned compositions may contain other matter in trace amounts without deleteriously affecting the utility of the compositions for the purposes above related, but such impurity should not exceed an order of magnitude of .01%, by weight, except for addition of positive promoters, of which, as examples, sodium and lithium may be present in amounts up to maximum concentrations of one atomic percent. The addition of positive promoter chemical elements, other than the elements manganese and tellurium of which the compositions mainly consist, are effective to enhance certain of the electrical properties of the thermoelectric elements.

The aforesaid thermoelectric elements 54 may be formed from the compositions aforementioned, and such compositions may be suitably prepared in the following manner:

The thermoelectric elements may be prepared by reacting pure unoxidized manganese directly with tellurium in appropriate proportions to afford the aforementioned range in a refractory container which does not react with the components. However, owing to inconveniences in preparing the elements with starting constituents of manganese and tellurium, it is preferable to first reduce commercial electrolytic manganese which normally contains a small amount of manganese oxide in a carbon crucible and an inert atmosphere, for a period of several minutes at a temperature of 2600° F. which converts all of the manganese oxide and metal to manganese carbide (Mn₃C). The manganese carbide and tellurium in suitable amounts to afford the aforementioned range of tellurium of from 69.9% to 72.0% by weight, balance manganese, in the end composition are then reacted in a carbon crucible under a suitable atmosphere such as hydrogen or Co₂. The aforementioned reaction between the manganese carbide and tellurium is violent and it is desirable that the crucible be fitted loosely with a carbon cap to prevent material from splattering out of the crucible. It is advantageous in carrying out the aforementioned reaction to use a tellurium excess over the amount of tellurium required to form the intermetallic compounds of manganese and tellurium of the aforementioned range of the order of 0.5 weight percent, or more, to insure the complete reaction with the manganese carbide. The rate of reaction of Mn₃C and Te or metallic Mn and Te is quite low, and the reaction rate can be raised substantially by increasing the proportion of tellurium in the initial melt over that desired in the final composition. The additional tellurium over and above the aforesaid range, present in the melt as undesirable excesses in the form of MnTe₂, may be removed to bring the composition within the aforementioned range of manganese and tellurium by vacuum melting of the material.

In such vacuum melting the equilibrium

is shifted to the right as the temperature is raised and the tellurium may be removed from the melt by reducing the pressure over the melt and allowing the tellurium to condense on a cooler section of the system. By holding the temperature of the melt above the melting point of MnTe (2150° F.) while reducing the pressure to the order of .1" Hg will, in several minutes, the time depending on how much tellurium is to be removed, bring the composition within the aforesaid range, and an almost pure metallographic phase will be produced, for which the vapor pressure of tellurium over the solid is negligible at temperatures up to its melting point.

When the thermoelectric elements 54 are of manganese and tellurium the aforementioned range is important. Should, for example, the manganese concentration ex-

ceed 30.1% by weight of the total composition of manganese and tellurium, such excess manganese, occurring as Mn₃C when the aforescribed method of preparation is followed, may be distributed throughout the ingot and tends to short circuit the thermal electromotive force. Further, as to tellurium excesses over and above 69.9% by weight of the total composition of manganese and tellurium combine with the single phase MnTe to form MnTe₂ which can be accommodated up to 72.0% tellurium by weight of the total composition of manganese and tellurium. Thus, unlike manganese excesses of the aforementioned range, the thermoelectric generator elements 54 can accommodate 8% by weight excess tellurium in the aforementioned form of MnTe₂ without appreciable significant reduction in thermoelectric power.

Turning again to the aforementioned method, it is expedient to incorporate all of the above operations of reducing, reacting, and removing excess tellurium to provide thermoelectric elements 54 within the above range of manganese and tellurium in one heating cycle. This can be done by putting appropriate proportions of manganese, carbide and tellurium in a closed carbon mold, and then heating the same to the order of 2600° F. for several minutes under an atmosphere of inert gas. The temperature is then reduced slightly and the mold is evacuated to remove the excess tellurium from the melt by vaporization. The released carbon from Mn₃C will form an insignificant scum on the surface of the solidified ingot.

The thermoelectric elements produced, as above discussed, may have their electrical conductivities increased by the addition, in a conventional way, of P-type additions or promoters, as for example, sodium or lithium up to concentrations of one atomic percent.

In the graph of FIGURE 3 of the drawings, the curve bearing reference numeral 80 generally indicates the thermo-electric power in microvolts per ° F. as against temperature in compositions of tellurium and manganese, in which tellurium ranges from 69.9% to 72.0% by weight, and the balance substantially all manganese. The curves indicated at 82, 83, 84 and 85 give the resultant characteristics of the additions of .03 atomic percent sodium or lithium; .1 atomic percent sodium or lithium; .3 atomic percent sodium or lithium; and 1.0 atomic percent sodium or lithium, to tellurium and manganese in the aforementioned range. The reduction of thermoelectric power as exhibited by FIGURE 3 by the utilization of positive promoter elements, as sodium or lithium, is accompanied by reduction in electrical resistivity as shown, for example, in FIGURE 4 by curves 86, 87, 88 and 89 respectively. In FIGURE 4, the general graphic representation of unpromoted tellurium and manganese in the range of from 69.9% to 72.0% tellurium by weight and balance substantially all manganese is exhibited by curve 90. In regard to the several curves of FIGURE 4, it will be readily apparent that they are characterized by desirable negative temperature co-efficients, it being observed that FIGURE 4 represents the log of the electrical resistivity expressed in ohm-inches plotted, as previously noted, for convenience against the reciprocal of absolute (Kelvin) temperature, symbolically expressed 10³T°K. It will be observed from an examination of FIGURES 3 and 4 that nominal loss of thermoelectric power is more than offset by reduced electrical resistivity of the promoted manganese-tellurium thermoelectric elements.

As previously indicated, any residual impurities occurring in electrolytic manganese is not effective to alter the conductivity of the thermoelectric elements of this invention as do the positive promoter elements sodium and lithium by reason of which elementary pure materials are not required in order to provide reproducible results, providing unknown or trace impurities do not exceed an order of magnitude .01% by weight of the manganese and tellurium.

Thermoelectrical elements produced in accordance

with the aforementioned methods are always P-type at all temperatures below the melting points of the compositions. The aforescribed thermoelectric elements may be operated at high temperatures, approaching 1600° F., without sublimation of the elements.

The contacts or electrodes 62 and 66 for thermoelectric elements 54 of the aforescribed compositions may be of steel or steel alloys having pressure engagement with the ends of elements 54.

Further, electrical contact may be made with thermoelectric elements 54 by fusing together the thermoelectric elements with an Mo—Fe electrode previously wetted with a small amount of a lead rich lead tellurium composition doped, for example, with sodium as disclosed in the Patent No. 2,811,440, dated October 29, 1957, and assigned to the assignee of this application. In this instance, the lead excess, lead-tellurium sodium doped composition acts as a solder joining the iron electrodes 62 and 66 and the thermoelectric element 54.

As previously noted in the utilization of thermoelectric elements of the aforescribed compositions at high temperatures, the thermoelectric elements should be hermetically sealed in an oxygen free environment.

If desired, annealing of the thermoelectric elements above described may be accomplished to the end of improving the same. This may be accomplished by annealing the thermoelectric elements for several hours at 1400° F. and allowing the thermoelectric elements to furnace cool with the operation being accomplished in a reducing atmosphere. The annealing step results in stabilizing the properties of the thermoelectric elements at high temperature operations.

In connection with thermoelectric elements in the range of from 69.9% to 72.0% tellurium, balance essentially all manganese, it has been observed that at the higher tellurium concentrations, operating temperatures may be somewhat limited by the vaporization of tellurium. However, where high temperature operation is not important, simplification of the production of the thermoelectric elements may be effected by the use of the greater amount of tellurium and eliminating the vacuum melting procedure without seriously affecting the electrical properties of the thermoelectric elements.

Thermoelectric elements of the aforescribed compositions are superior to other presently known thermoelectric materials at temperatures above 800° F. And, it is believed that such thermoelectric elements are capable for a hot junction operating temperature approaching 1600° F.

When the aforescribed manganese-tellurium compositions are utilized for thermoelectric elements 54 it is preferred that thermoelectric elements 53 be of negative polarity to afford efficient production of thermoelectric current by the thermoelectric generator. For this purpose thermoelectric elements 53 may be of steel or steel alloys.

It will be understood that various other thermoelectric materials may be utilized in my invention and the aforescribed manganese-tellurium compositions and steel afford a preferred embodiment of my invention. Also contact electrodes 62 and 66 may comprise any contact material suitable for use with the selected thermoelectric materials and the materials for contacts 62 and 66 hereinabove described have utility for the disclosed manganese-tellurium compositions.

In the construction of a control system in accordance with the above a control circuit was afforded having a cold resistance of 1.8 ohms and an operating resistance with the hot thermojunctions of the generator at a predetermined satisfactory operating temperature of .2 ohm which it will be readily apparent to those skilled in the art is amply effective to achieve the operation of the control system as above described, I claim:

1. An electrical circuit comprising a load device, electrical energy source means including a thermoelectric

generator in circuit with said load device for energization thereof, said generator having hot junction means and said source means affording a predetermined value of electrical energization to said load device when said hot junction means is subjected to a predetermined operating temperature level, said generator including at least one thermoelement of material having a high negative temperature coefficient of resistance at and below said operating temperature level and being connected in said circuit in such a manner that on a decrease in the temperature of said thermojunction means from said predetermined operating level, the resultant increase in the resistance of said one thermoelement effects a substantial decrease in the electrical energy supplied to said load device, irrespective of any concomitant variation in the electrical output of said generator.

2. An electrical circuit including at least one thermoelectric generator as a power source therefor, said one generator having hot junction means and said circuit having a predetermined value of operating resistance when said hot junction means is subjected to a predetermined operating temperature level, said one generator including at least one thermoelement of material having a high negative temperature coefficient of resistance at and below said operating temperature level causing, on a decrease in the temperature of said thermojunction means from said predetermined operating level, a substantial increase in the resistance of said circuit.

3. A control system comprising, control means having coil means of predetermined operating current value, a plurality of thermoelectric generators in circuit with said coil means each having thermoelectric elements, thermoelectric properties and at least one of which generator has a thermoelement having a negative temperature coefficient of resistance at and below a predetermined operating temperature, said thermoelectric elements of each generator being joined to afford hot thermojunction means for each of the respective generators for heating to operating temperature by different heat sources, whereby when the hot thermojunction of said at least one generator is at a temperature below said predetermined operating temperature, said thermoelectric element thereof which has the negative temperature coefficient of resistance effects an increase in the resistance of said circuit to afford a current therein of a value lower than said predetermined operating current value for said coil means.

4. In combination, a plurality of primary burners, an ignition burner for each of said primary burners, main control valve means including coil means for controlling the flow of fluid fuel to said main burners, a thermoelectric generator at each of said ignition burners having hot thermojunctions adapted to be heated to a predetermined normal operating temperature by the latter, means connecting said thermoelectric generators in circuit with said coil means of main control valve means, and said thermoelectric generators each including at least one thermoelectric element having a negative temperature coefficient of resistance at and below said predetermined normal operating temperature and adapted upon a predetermined reduction in said hot thermojunction temperature to afford said circuit means increased electrical resistance characteristics causing substantial de-energization of said coil means of said main control valve means to terminate the flow of fluid fuel to said primary burners.

5. In combination, a plurality of heat sources, a plurality of thermoelectric generators one for each heat source, said thermoelectric generators each comprising a plurality of thermoelectric elements of different thermoelectric properties connected to afford hot thermojunction means for heating to a predetermined normal operating temperature by said heat sources, each of said generators having at least one thermoelectric element which has a negative temperature coefficient of resistance at and below said normal operating temperature, a safety device, circuit means connecting said thermoelectric generators

and said safety device, said safety device being adapted to be energized by the thermoelectric current produced by said thermoelectric generators, and said one element of each of said thermoelectric generators affording increased resistance to said circuit means for de-energizing said safety device when the temperature at its associated hot thermojunction drops below said predetermined operating temperature.

6. In combination, a burner, main control valve means including coil means for controlling the flow of fluid fuel to said burner, a thermoelectric generator at said burner having a hot thermojunction adapted to be heated to a predetermined normal operating temperature by the burner, means connecting said thermoelectric generator in circuit with said coil means, and said thermoelectric generator including a thermoelectric element having a negative temperature coefficient of resistance at and below said predetermined normal operating temperature and adapted upon a predetermined reduction in said hot thermojunction temperature to afford said circuit means increased electrical resistance characteristics causing substantial de-energization of said coil means of said main control valve means to terminate the flow of fluid fuel to said burner.

7. In combination, a heat source, a thermoelectric generator comprising a plurality of thermoelectric elements connected to afford hot thermojunction means to be heated to a predetermined normal operating temperature by said heat source, said generator having at least one thermoelectric element which has a negative temperature coefficient of resistance at and below said normal
